ADJUSTABLE SHOE TREE

Robert Hubbert, Grosse Pointe, Mich.

Application December 17, 1945, Serial No. 635,487

3 Claims. (Cl. 12—128.6)

1

The invention relates to shoe trees and has for one of its objects to provide an improved shoe tree in which the toe and heel pieces may be readily adjusted toward and away from each other.

The invention has for another object to provide an improved adjustable connection between the toe and heel pieces which may be easily adjusted.

The invention has for a further object to form the connection between the toe and heel pieces in the nature of a toggle joint to facilitate insertion and removal of the shoe tree into and from a shoe.

These and other objects of the invention will become apparent from the following description, taken in connection with the accompanying drawings, in which

Figure 1 is a plan view of a shoe tree embodying the invention;

Figure 2 is a side elevation thereof;

Figures 3 and 4 are cross sections on the lines 3—3 and 4—4, respectively, of Figure 1;

Figure 5 is a cross section on the line 5—5 of Figure 2;

Figure 6 is a cross section on the line 6—6 of Figure 4.

The shoe tree comprises the toe piece 1, the heel piece 2 and the adjustable connecting device 3.

The toe piece is formed of the lower and upper sheet metal sections 4 and 5, respectively, integrally connected by the end wall 6, the lower section having the inwardly offset upper edge portion 7 over which extends the lower edge portion 8 of the upper section. These sections are secured together by forming their overlapping portions with the abutting tongues 9 which are sheared from the overlapping portions of the lower and upper sections. The end wall 6 is provided with the reinforcing ribs 10 depressed toward the front of the toe piece and the boss 10' between the ribs 10 and depressed rearwardly. The toe piece is hollow and the lower and upper sections 4 and 5 are formed with the longitudinally extending slots 11 and 12, respectively, and the end wall 6 is of less width than the rear end of the toe piece to provide for circulation of air.

The heel piece 2 is formed of sheet metal and is hollow and is open toward the toe piece.

The adjustable connection 3 comprises the sheet metal clamping member 13 which is formed with the flat top 14, the depending end wall 15 spaced from each other and also the depending resilient wings 16 which normally diverge downwardly with respect to each other. The end walls are formed with the aligned openings 17 and the

2

wings are formed with the aligned openings 18 and terminate at their lower ends in the curved finger grips 19. The device also comprises the rods 20 and 21, both of which are U-shaped. The rod 20 has the base 22 of its U extending through the openings 17 in the end walls 15 and has the free end portions 23 of its legs extending toward each other and extending through openings in the side walls of the boss 10' of the toe piece in the rear of the reinforcing ribs 10, the construction being such that the rod 20 is pivotally connected to both the toe piece 1 and the clamping member 13. The rod 21 has the free end portions of its legs fixedly connected to the heel piece 2 by means of the tongues 25 struck out from the top of the heel piece and the tongues 26 struck out from the rear wall of the heel piece. The legs of this rod extend through the openings 18 in the wings 16 and are formed in advance of the clamping member 13 to extend upwardly with the upper end portions connected by the base 27 of the U of the rod. These upwardly extending portions and base form a finger grip to facilitate insertion of the shoe tree into a shoe and also removal from the shoe.

For the purpose of strengthening the U-shaped rod 20 and holding its legs from spreading apart, I have preferably provided the transverse rod 28 which is located below and extends transversely of 30 and is fixedly secured to the legs of the rod 20 as by being welded thereto.

With the above construction, the adjustable device 3 is in the nature of a toggle joint which, when the parts are in operative position in the shoe, has the pivotal connection between the rods 20 and 21 located below the line of the pivotal connection of the rod 20 to the toe piece 1 and the fixed connection of the rod 21 to the top of the heel piece 2. By pulling upwardly on the base 27 of the U-shaped rod 21 the toggle joint can be readily broken, at which time the heel piece pivots with the rod 21 until the pivotal connection between the rods has been elevated sufficiently to permit ready removal of the heel piece from the shoe, after which the toe piece may be withdrawn. To insert the shoe tree the toe piece is first inserted into the shoe and then the heel piece is inserted, after which the knee of the toggle joint is depressed to locked position of the toggle joint. It is apparent that by moving the finger grips 19 toward each other the wings 16 release the legs of the rod 21, after which it may be longitudinally adjusted and then the finger grips released so that the wings will resiliently clamp the legs of the

rod 21 to hold it in adjusted position relative to the member 13.

What I claim as my invention is:

1. A shoe tree comprising a hollow sheet metal toe piece, a hollow sheet metal heel piece, a sheet metal member having spaced end walls formed with aligned openings and also having resilient diverging wings, a U-shaped rod having its base extending through the openings in said end walls and the free ends of its legs pivotally connected to said toe piece, and a U-shaped rod fixedly connected to said heel piece and having its legs extending through the openings in and adjustably clamped by said wings.

2. A shoe tree comprising a toe piece, a heel piece, a rod pivotally connected to said toe piece, a member having spaced end walls for pivotally engaging the free end of said rod and also having resilient diverging wings and a second rod connected to said heel piece and extending through and adjustably clamped to said wings.

3. In a shoe tree comprising a toe piece and heel piece, each having a rod extending therefrom, the combination of a member having spaced

end walls formed with aligned openings therein for receiving the free end of one of said rods and also having resilient diverging wings having aligned openings therein for receiving and adjustably clamping said other rod.
